(57) **CLAIM**

The ornamental design for a hotel door sound suppressor (HDSS), as shown and described.

DESCRIPTION

FIG. 1 is a perspective view of hotel door sound suppressor (HDSS) showing our new design, attached to an inside frame of a door;

FIG. 2 is a perspective view thereof, attached to door latch, showing frame side and door side portions of HDSS;

FIG. 3 is a perspective view of frame side portion of HDSS;

FIG. 4 is a front elevational view of FIG. 3;

FIG. 5 is a rear elevational view of FIG. 3;

FIG. 6 is a left side elevational view of FIG. 3;

FIG. 7 is a right side elevational view of FIG. 3;

FIG. 8 is a top plan view of FIG. 3;

FIG. 9 is a bottom plan view of FIG. 3;

FIG. 10 is a perspective view thereof, attached to an outside of door side;

FIG. 11 is a perspective view of door side portion of HDSS, shown in FIG. 10;

FIG. 12 is a front elevational view of FIG. 11;

FIG. 13 is a rear elevational view of FIG. 11;

FIG. 14 is a bottom plan view of FIG. 11;

FIG. 15 is a top plan view of FIG. 11;

FIG. 16 is a right side elevational view of FIG. 11; and,

FIG. 17 is a left side elevational view of FIG. 11.

The broken lines showing of an environment of door latch and door are for illustrative purpose only and form no part of the claimed design.
